UNITED STATES PATENT OFFICE.

ALONZO E. PORTER, OF POMPTON LAKES, NEW JERSEY, ASSIGNOR OF ONE-FOURTH TO
EUGENE P. SEARING, OF JERSEY CITY, NEW JERSEY; MARY LE FEVRE PORTER
ADMINISTRATRIX OF SAID ALONZO E. PORTER, DECEASED.

FUSE.

956,996.

Specification of Letters Patent.

Patented May 3, 1910.

Application filed June 29, 1908. Serial No. 440,955.

To all whom it may concern:

Be it known that I, ALONZO E. PORTER, a citizen of the United States, and a resident of Pompton Lakes, county of Passaic, and 5 State of New Jersey, have invented certain new and useful Improvements in Fuses, of which the following is a full, clear, and exact description.

This invention relates more particularly 10 to fuses for exploding dynamite.

The primary object of the invention is to provide a simple and efficient device in which the terminals for igniting a fulminate or explosive may be properly held within a 15 metallic shell or casing, and so arranged that the fulminate will be properly protected from moisture or water in order that the same may be made to cause the fuse to explode dynamite or other explosives.

20 A further object of the invention is to provide simple and efficient water-proof fuse in which the terminals may be held in an absorbent or compressible material so as to properly seal and inclose a fulminate within a casing.

With these and other objects in view, the invention will be hereinafter more particularly described with reference to the accompanying drawings, which form a part of 30 this specification, and will then be pointed out in the claims at the end of the description.

In the drawings, Figure 1 is a side elevation of one form of device embodying my 35 invention. Fig. 2 is a longitudinal section, partly in elevation, of the device shown in Fig. 1. Fig. 3 is a plan view of Fig. 1. Fig. 4 is a side elevation of a different form of fuse casing. Fig. 5 is a plan view; and 40 Fig. 6 is a longitudinal section, partly in elevation, of the fuse shown in Figs. 5 and 6.

The device 10 has a tubular shell or casing 11, provided with a substantially cylindrical body portion 12, the lower end of 45 which is closed, as at 13, and within the body portion 12, is arranged a fulminate 14 which may consist of compressed powder 15, and loose or free powder 16 as is usual, and within the body portion 12 is adapted to be forced a plug 17 of wood, cork, soft white or cork pine, or other material. This plug or member 17 may have a plurality of holes 18 through which pass the ends of the terminals 19 and 20 which may be connected

to any suitable source of electric supply in 55 order that the current through the terminals may cause the fulminate to explode as is usual in fuses of this character, the said terminals being connected by a platinum wire 21 or other means to cause the fulminate to 60 be ignited.

The casing 10 above the cylindrical body portion 12 is provided with an annular rib 22 forming an inner annular groove above which is arranged an enlarged mouthpiece 65 or end 23, which at its lower end is inclined at an angle, as at 24. The member or element 17 of wood or other material is made somewhat larger than the interior diameter of the body portion 12, so that said 70 plug member or element may be forced under pressure within said cylindrical portion to seal the same above the fulminate, the inclined portion 24 serving to better guide and permit the plug member to be forced 75 inwardly with the terminals to the position shown in Fig. 2, and after the plug has been forced within the cylindrical body portion 12 the outer end is sealed with sulfur, as at 25, or with any other material. 80

The element 17 when of cork will prevent all moisture from passing by the same, and when wood is used it will act as an absorbent to gather any moisture and prevent the same from reaching the terminals or the fulminate, and the said wood plug may be forced 85 so as to be compressed within the body portion, or may be made to simply fit the same tight or in any other desired way. By this means the fuse becomes water-proof, and 90 overcomes the objections to fuses as ordinarily constructed.

When the fuse is in use it is ordinarily placed in a stick of dynamite or otherwise arranged so that when the current is made 95 to pass through the terminals 19 and 20, the fulminate will be ignited and by reason of the concussion will explode the dynamite in the usual manner.

In Figs. 4 to 6, the plug member 26 is of 100 wood or like material, and the terminals are held therein in substantially the same way as shown in Fig. 2 in which the holes may be slightly tapered or enlarged at one end to provide a better seal for the terminals in 105 passing therethrough, and instead of the form of casing or shell shown in Fig. 2, the shell 27 is substantially cylindrical through

out its entire length and has an annular enlarged portion 28 serving to hold the sulfur or sealing material within the shell. In this form the plug or element 26 is intended to fit either tight or loose within the casing 27, and is of such material as will absorb any moisture that might come in contact therewith.

It is to be understood that the word "fulminate" is employed in its broadest sense to include any explosive mixture that may be used in the casing of the fuse; and where the word "wood" is used this is intended to include "cork".

From the foregoing it will be seen that simple and efficient means are provided whereby an inexpensive effective fuse is made thoroughly water-proof so that all possibility of the fuse not igniting the explosive mixture is overcome no matter whether the said fuse is submerged in water or not; that said construction permits the fuse to be used in the usual manner; and that said fuse is so made that it will keep and be ready for use after many years as it is not injuriously affected by weather, moisture or similar conditions.

Having thus described my invention, I claim as new and desire to secure by Letters Patent:

1. A fuse comprising a casing having a substantially cylindrical body portion with one end closed, an enlarged mouth portion having an inclined lower part, and an annular rib forming an annular groove below the mouth portion, a fulminate contained within the casing, terminals arranged in the casing, a plug member having openings therethrough for the reception of the ends of the terminals and adapted to be passed into said

casing through the open end and to seal the body portion of the casing above the fulminate within the casing and a filling arranged above the plug member.

2. A fuse comprising a casing having a body portion, an enlarged mouth portion having an inclined lower part, and an annular rib forming an annular groove within the casing below the mouth portion, a fulminate within the casing, terminals arranged in the casing, and a plug member having openings therethrough for the reception of the ends of the terminals.

3. A fuse comprising a casing having a body portion, an enlarged mouth portion, and an annular rib below the mouth portion, a fulminate within the casing, terminals arranged in the casing, a plug member of compressible material holding the ends of the terminals and adapted to seal the body portion of the casing above the fulminate and filling arranged above the plug member.

4. A fuse comprising a casing having a substantially cylindrical body portion with one end closed, an enlarged mouth portion having an inclined lower part, and an annular rib forming a groove below the mouth portion, a fulminate within the casing, terminals arranged in the casing, a wood plug member holding the ends of the terminals adapted to be passed into the casing through the open end and a filling arranged above the plug member within the casing.

This specification signed and witnessed this twenty-sixth day of June A. D. 1908.

ALONZO E. PORTER.
